UNITED STATES PATENT OFFICE.

MARCI STEFANSKI, OF STERLING, MICHIGAN.

TELESCOPIC BED.

1,315,170.

Specification of Letters Patent.

Patented Sept. 2, 1919.

Application filed May 10, 1919. Serial No. 296,181.

To all whom it may concern:

Be it known that I, MARCI STEFANSKI, a citizen of the United States, residing at Sterling, county of Arenac, and State of Michigan, have invented certain new and useful Improvements in Telescopic Beds, of which the following is a specification.

This invention relates to improvements in articles of furniture, and particularly to beds.

10 The principal object of the invention is to provide a bed frame which may be drawn laterally outward, so as to accommodate two or more persons, or collapse to form a single bed.

15 A further object is to provide means whereby the frame elements when extended are held from inadvertently collapsing or held confined when in a closed position, which is the normal condition of the bed.

20 These and other like objects are attained by the novel construction and combination of parts hereinafter described and shown in the accompanying drawings, forming a material part of this disclosure, and in which—

25 Figure 1 is a perspective view showing a bed frame made in accordance with the invention, the parts being in a folded position.

30 Fig. 2 is an end view of the same shown in an extended position, parts being broken away in order to disclose the construction.

35 Fig. 3 is a transverse sectional view taken on line 3—3 of Fig. 2.

Fig. 4 is a further enlarged fragmentary longitudinal sectional view showing the construction of parts, and

Fig. 5 is a plan view of the mattress used in connection with the frame.

Referring to the drawings, the numeral 10 indicates the posts of the bed, preferably of the usual tubular metallic construction, surrounded by ornamental knobs 11, and provided with casters 12 at their lower ends so that the bed frame may be readily moved from place to place upon the floor of the room. These posts are preferably higher at the head than at the rear, and are connected by longitudinal rails 14, as is usual in metal beds of this type of construction.

50 Engaged with each of the posts 10 are pairs of tubular elements 15 and 15', respectively near the upper and lower parts of the posts, the same being of such length that when the bed is in a collapsed or folded po-

sition, as shown in Fig. 1, the ends of the 55 tubes are in intimate contact so that no break or opening appears between them.

A pair of bars 18 and 18', formed with forks 19 at each of their ends, are adapted to enter the open ends of the tubular elements 15 and 15', and journaled in the forks, on the pins 20, are rollers 21, having curved faces and adapted to fit neatly within the tubes.

Secured near the upper sides of the bars 18 and 18', are flat springs 23, having angular projections 24 at their outer free ends, upon which are mounted small sleeves 25, engageable in openings 26 or 27, formed in the tubular elements 15 and 15', the openings 26 being near their outer ends, while the openings 27 are relatively close to the posts 10 so that when the spring carried sleeves 25, which act as detents, are engaged in the openings 26, the head and foot elements of 70 the bed frame are held in an extended position, and conversely, when the sleeves are engaged in the openings 27, the head and foot elements are held closely together.

In order to hold the extending tubular elements 15 and 15' in proper spaced relation, and also for in the ornamental effects obtained, they are connected by vertical rods 28, while a single vertical rod 30 engages between the bars 18 and 18', recesses 31 being provided in the opposed sides of the tubular elements, at their ends, into which the rods 30 enter when the frames are in a closed position.

90 A wire or like mattress 40, provided with side elements 41, is adapted to be used in connection with the bed frame, the side elements 42 and 43 being connected by headed pins 44, slidably in the slots 45, the pins being rigidly set in the elements 42, while the 95 slots are formed in the corresponding elements 43, thus permitting the mattress to be collapsed or extended as indicated best in Fig. 5.

From the foregoing it will be seen that a 100 convenient bed frame has been disclosed which, in addition to its use for a single person, may be extended by merely depressing the detents 25, and drawing the sides apart, whereupon the detents enter into the outermost openings, formed in the tubular end elements, holding the same extended so that the bed may be used for two or more persons.

Having thus described my invention what I claim as new, and desire to secure by Letters Patent, is—

In a folding bed, the combination with 5 the corner posts thereof and longitudinal rails connecting therebetween at the sides, of pairs of parallel tubular elements secured laterally on each post extending toward each other, bars having forked ends, rollers carried 10 in the forks of said bars engageable

within said tubular elements, spring actuated detents carried by said bars engageable in openings formed in the upper sides of said tubular elements, connections between said tubular elements, and connections between said bars whereby they are moved in unison. 15

In testimony whereof I have affixed my signature.

MARCI STEFANSKI.

Copies of this patent may be obtained for five cents each, by addressing the "Commissioner of Patents, Washington, D. C."
